TOOL FOR WRAPPING SLIT TUBING

David V. Benfer, 131 Ridgeview Drive, Marysville, Pa.

Filed Nov. 7, 1958, Ser. No. 53,287

Term of patent 14 years

(Cl. D54—13)

FIG. 1 is a perspective view of a tool for wrapping slit tubing showing my new design;

FIG. 2 is a front elevational view thereof, and;

FIG. 3 is a side view thereof.

I claim:

The ornamental design for a tool for wrapping slit tubing, substantially as shown.
